UNITED STATES PATENT OFFICE.

JOSEPH W. ANTHONY, OF LYNN, MASSACHUSETTS.

LEATHER-FOLDING MACHINE.

1,386,676.

Specification of Letters Patent. Patented Aug. 9, 1921.

Application filed July 15, 1918. Serial No. 244,842.

To all whom it may concern:

Be it known that I, JOSEPH W. ANTHONY, a citizen of the United States, and a resident of Lynn, county of Essex, and State of 5 Massachusetts, have invented an Improvement in Leather-Folding Machines, of which the following is a specification.

My invention relates to leather folding machines and is designed to be an improvement 10 on the machines described and claimed in my previous patent applications: Serial No. 79,205, Patent 1,326,826, filed Feb. 18, 1916; Serial No. 155,343, Patent 1,365,648, filed March 16, 1917; Serial No. 155,344, 15 Patent 1,326,827, filed March 16, 1917; Serial No. 155,345, Patent 1,326,828, filed March 16, 1917; Serial No. 224,224, filed March 23, 1918, and more particularly it is an improvement of the machine described in 20 said last application.

The machines described in said applications are adapted for the folding of leather, flexible fabric, or similar material, to form one or more folded edges and also to form a 25 crease or ornamental marking on the folded edge. Each machine has, as elements, a material clamping means, a fold defining means, a folding means, and a creasing means, although the creasing means may be 30 omitted if the ornamental marking is not desired. Inasmuch as a machine of the type specified is designed to fold the material to differing dimensions as, for instance, in the manufacture of a line of book covers, small 35 pocket books, and the like, it is desirable that the component parts of the machine which operate upon the material be adjustable in order that said component parts may be moved relatively to each other to condition 40 the machine for the folding of material to differing dimensions, and with but the minimum number of elements which correspond to each size of folded product and which must be removed and replaced by a 45 new part of a size corresponding to the size of the new article to be manufactured.

Specifically my invention relates to a 50 presser head designed to replace the head of the machine described in the last above named application and the object of my invention is the provision of means whereby the elements carried by said head are relatively adjustable to thereby condition said elements for operation upon material for the 55 folding thereof to differing dimensions.

The means whereby I accomplish this

object of my invention is by forming the respective elements in segments, or separate portions, which are relatively movable to thereby change the dimensions of the elements and which overlap or overslide relative to another, thereby permitting of expansion or contraction of said elements without interrupting or causing a break in its contour or surface. Said presser head carries a clamping plate which is movable into engagement with unfolded material placed on a material table therebeneath to secure said material to said table for operation thereon; and fold defining means which comprise forming plates arranged on and above said clamping plate and which serve to define the folding edge.

A further object of my invention is the provision of means whereby said elements 75 are operated in their respective order. The forming plates are extensible to define the line of fold and are retractable from the fold to permit further operation of the machine.

It is desirable that said forming plates be 80 locked in their fold defining position in order that they may always define the same dimension of folded edge and not be moved from their initial set position during a succeeding operation of the machine.

A further object of my invention therefore is the provision of locking means for the fold defining means in their extended position.

I accomplish this object of my invention 90 by the provision of a slot or recess in the operating member controlling the movement of said folding defining means into which a key is adapted to drop when said fold defining means are in their extended position 95 to thereby lock said means in said position. Unlocking means are provided which are operated from a component part of the operating mechanism previous to the engagement of said mechanism with the fold defining means operating member to move said fold defining means from the folded edge.

It is desirable that the fold defining means or forming plates be extended to fold defining position after the clamping plate has 105 been raised to its original position or during the latter part of its movement into such position to thereby again present a line of fold.

Consequently a yet further object of my invention is the provision of means whereby 110 I accomplish this result, which means comprises a connection between the clamping

plate operating member and the forming plate operating member, whereby the movement of said clamping plate member to raise said clamping plate serves to actuate the forming plate member to extend said forming plates.

Figure 1 is a plan view of a folding machine embodying my invention.

Fig. 2 is a plan view of a presser head and associated mechanism embodying my invention.

Fig. 3 is a side elevation of Fig. 2.

Fig. 4 is a sectional elevation along lines 4-4, Fig. 2.

Fig. 5 is a sectional plan detail along lines 5-5, Fig. 4 showing the presser base, certain elements carried thereby being removed.

Figs. 6 and 7 are a plan view and side elevation respectively of a modified form of forming plate.

Fig. 8 is a front elevation of the presser head.

As here shown the machine includes the table 10 upon which is arranged the mechanism for performing the various operations upon the material. Said mechanism is driven from motor 11 arranged on said table and connected through belts 12 and 12^a and gears 13 and 13^a with a cam shaft 14, from which cam shaft the operation of the various parts of the mechanism is controlled. Said belts and gearing form a convenient means of reducing the relatively high speed of the motor to a suitably low speed for driving the machine although it is obvious that other means may be employed. A cam disk 15 having the cam path 16 is fixed to said shaft 14 and serves to actuate and govern the movements of the mechanism.

It is desirable that means be provided whereby the mechanism may be stopped at the end of one cycle of operation to permit the removal of the folded material and the insertion of an unfolded blank and after the mechanism is started in operation to continue in operation and stop at the end of the complete cycle in condition for the insertion of new material. It is also desirable that the mechanism be stopped at some intermediate operation of the machine, as for instance, after the material has been folded, and while the creasing iron is in contact with the folded edge, to thereby provide sufficient time for the firm adherence of the folded edge to the main body of the material and to heat the folded edge to thereby receive a well defined crease or ornamental marking. To accomplish these results the gear 13 is arranged on said shaft 14 to rotate either independently of said shaft with continued rotation of the motor or to rotate with said shaft to actuate the component parts of the machine and clutching means are provided to control the driving connection between said gear and shaft.

The clutching means comprises a pin and slot device of the type common in punch presses and similar machines and is believed not to need description especially as the specific construction is not essential.

The cross head 35 is slidably arranged on ways 36 of the frame of the machine and forms means by which the operation of the various elements of the machine are controlled. A pin 37 secured in said cross head 75 bears a roller 38 which extends into the cam groove 16 of said cam disk 15. Said cross head 35 is formed with a gear portion 39 which meshes with a corresponding gear portion 40 formed on the arm 41 which is 80 upwardly extended from the periphery of the operating ring described in the above-named application which controls the movement of the wipers and creasing iron. A reciprocating movement of said cross head 35 causes an oscillatory movement of the operating ring whereby to reciprocate, through cams, the wipers and creasing iron.

A presser arm 45 flanged and ribbed for strength and lightness is secured to the table 90 or base 10 of the machine and extends over said bed or table and terminates in spaced apart vertical walls 48. Blocks 49 are secured in the adjacent faces of said walls 48 by means of bolts 50 and said blocks have 95 grooves 51 therein which form ways in which the presser head is slidably arranged.

It is desirable that the presser head be movable from its position above the table of the machine to permit access to the various elements of the machine operable upon the material and for this purpose the presser arm is pivotally secured to the bed or table of the machine, and is movable about the pivot pin 17 extended between the base 18 of 105 the presser arm and the bed or table 10 of the machine.

Bolts 20 extend through the base of the presser arm and screw into the bed or table 10 of the machine to secure the presser arm 110 thereto in proper position above the table and other bolts 21 are passed through arcuate slots 22 in the base of said presser arm and are screwed into the bed or table 10.

While both sets of bolts 20 and 21 serve to 115 secure the presser arm to said bed or table in the proper position of said arm to permit the operation of the various operating elements carried thereby upon the material, bolts 21 in addition serve to align the presser arm in 120 its correct position over the material table.

With the provision of the arcuate slots 22 in which the bolts 21 are arranged, it is not necessary to completely remove said bolts to permit the moving of the presser arm. 125

The pivot pin 17 is eccentrically located in the base of the presser arm whereby the arm may be moved toward the left, see Fig. 1, without any part thereof engaging the cam disk 15, which would prevent farther move- 130

ment, as would be the case if the pivotal connection with the bed or table 10 of the machine were centrally located with respect to the presser arm.

5 Said presser head has a base portion of more or less hexagonal form with a bottom wall 52 and side walls 53. Said head is formed with two vertically extended arms 54 having V shaped portions 55 which are slidably arranged in the ways 51 of said presser arm. A cross member 56 serves to connect the top ends of said arms 54 and is secured to said arms by the bolts 57 and thereby forms a rigid structure.

10 15 Said presser head is adapted to be permitted to drop vertically downward in the ways 51 in said presser arm to thereby clamp material between a clamping plate carried by it and the material table 60 arranged beneath said presser head and to be moved vertically upward in its ways during a certain part of the cycle operations of the machine to permit the release of the finished material from the machine.

20 25 The movements of said presser head are controlled by the cam block 61. Said block is arranged between the vertically extended arms 54 of the presser head and is supported in the channel formed by the bottom wall 62 and connected side walls 63 which are integral with the presser frame. Said cam block is slidably arranged in a groove 64 in the bottom wall 62, and a cross bar 65 secured between said side walls 63 serves to restrain said cam block 61 therein, but does not restrain its reciprocatory movements. The cross member 56, secured between the vertically extended side arms 54 of the presser head, is formed with two spaced 30 35 apart downwardly extended lugs 66 which extend into the space between said cam block 61 and the side walls 63 and between which said cam block 61 is slidably arranged. A pin 67 extends between said lugs 66 and a roller 68 is arranged thereon between said lugs.

40 45 Said cam block 61 is formed with a cam slot 70 therein which is preferably arranged substantially at forty-five degrees with the path of movement of said cam and said roller 68 of the presser head is arranged therein.

50 55 It is seen that as cam block 61 is moved to the left from the position shown in Fig. 4, the presser head is permitted to move downward to secure the material arranged on the material table beneath said presser head to said table and a movement of the cam in the opposite direction causes an upward movement of the presser head to cause the unclamping of the folded material.

60 65 While said cam block 61 controls the movement of the presser head toward and away from the material on the table arranged therebeneath, yet the extent of such

movement is fixed. It is desirable that the extreme low position of the presser head be varied thereby to condition the machine for the folding of material of differing thicknesses as it may be readily seen that an adjustment of the machine suitable for one thickness of material will not be correct for thicker or thinner material and with a thicker material, for instance, the maximum depression of the head will be insufficient and the wipers will cut the edge of the material in the folding operation.

70 75 Means are therefore provided whereby the lowest operated position of the presser head may be adjusted. Such an adjustment may be accomplished by varying the position of said cam block 61 on its operating rod 71 either at its immediate connection with said rod or, what is the equivalent, at the connection of said rod 71 with the member 74, 80 or otherwise, I prefer, however to make such adjustment by means of shims 80 inserted between the cross member 56, the movements of which are controlled by the cam block 61, and the arms 54 of the presser-head. It may 85 be seen that by inserting shims therebetween, the presser-head will be moved a correspondingly greater distance downward than before, and if shims are removed, or the thickness of the shims are decreased, then the 90 presser head will be moved a correspondingly less distance downward.

95 100 Movements of the cam block 61 are controlled through the upper cam rod 71 which is slidably arranged in bearings in cross ribs 72 of the presser arm and which is fixed into said cam block 61 by means of set screws 73. Said upper cam rod 71, at its farther end, is connected through the arm 74 with an extension 75 arranged in the lower part of 105 said presser arm and slidably arranged in a cross rib 76 thereof. A pin 77 is downwardly extended from said extension 75 and a cam roller 78 is arranged thereon which is disposed in the cam groove 79 of the cam 110 block 80.

115 Said cam block 80 is spaced above a second cam block 85, hereinafter to be more fully described, by the spacer block 86 and said cam blocks and spacer block are secured by means of screws 87 to the sliding cross head 35, the movement of which is controlled by the cam disk 15.

120 125 A roller 88 is loosely arranged in a member 89 secured to the presser head and bears against the end of said cam block 80 to serve as a thrust bearing to prevent the cramping of said block when it is reciprocated by said cross head 35. A screw 90 having an enlarged head is arranged in said member 89 125 with its head overlapping said roller 88 to thereby retain said roller in its groove.

130 When it is desired to swing the presser arm 45 from its normal position, to a position away from the material table, which

movement is permitted by removing the bolts 20 and loosening the bolts 21, it is also necessary to disconnect the two cam blocks 80 and 85 from the cross-head 35 inasmuch as said blocks are arranged on the base of said presser arm. This disengagement is performed by removing the screws 87 which pass through said blocks into the cross head, thereby entirely freeing the mechanism carried by the presser arm from connection with other parts of the machine.

The diagonally opposite corners of the base of the presser head are formed with extensions 95, in the end faces of which are formed dovetailed ways 96 in which are reciprocatingly arranged the sliding members 97. Said sliding members are adapted to be moved outwardly or inwardly of said presser base to extend or retract the fold defining means or forming plates carried at the extremities thereof.

Said sliding members 97 are formed with dovetailed lower faces on which are adjustably arranged adapting plates 98 which are provided with dovetailed slots 99 therein corresponding to the grooves on said members. The under faces of said adapting plates 98 are formed with dovetailed grooves 100 therein, the axes of which are angularly related to the longitudinal axes of said plates and corner forming plate brackets 101 having dovetailed surfaces 102 are adjustably arranged in said grooves 100 of said adapting plates 98. Said forming plate brackets 101 are formed with right angled edges to which are secured the forming plates 105 which are formed of thin material and present two lines of fold at right angles to each other although it is obvious that the shape of the folding edge may be varied as desired.

It is seen that, by the provision of adapting plates which are slidably related to the sliding members 97, the forming plates may be diagonally moved or adjusted to thereby increase or decrease the dimensions of the folding edge which they define in an extended position. Since the forming plates, or the brackets 101 which support said forming plates, are slidably arranged on said adapting plates and relatively movable therewith, the length of two sides of the fold may be adjusted without necessarily changing the length of the other two sides of the fold.

A bolt 106 passing through said sliding members 97, the adapting plates 98, and forming plate brackets 101 serve to lock all of said members in any adjusted position, and slots 107 in said forming plate brackets permits a movement of said forming plates relative to said sliding members 97 to permit the desired adjustments of said forming plates.

The ends of the forming plates 105 are

adapted to lap over one another in both the extended and retracted positions thereof and have their contiguous ends oppositely tapered to thereby reduce the total thickness of metal at the overlapping points.

The forming plates shown in Fig. 5 are suitable for the defining of a line of fold to a number of different dimensions. They will not, however, take care of all of the work which is required to be performed on this machine and for work upon smaller sizes, a different or modified set of corner plate brackets and forming plates are necessary. Figs. 6 and 7 show such modified brackets and forming plates.

It is seen that these brackets and forming plates are similar in general construction and appearance to the forming plates and brackets shown in Fig. 5 with the difference that, whereas in Fig. 5 the forming plates are at the extremities of the reciprocating members 97, in the modification they are arranged beneath the inner ends of said members and are arranged to be moved outwardly and inwardly in exactly the same manner. It is obvious that the lengths of the two sides of the forming plates may be made of any suitable length for the folding of material to many differing dimensions.

The reciprocatory movements of the reciprocating member 97, which control the movements of the forming plates, are controlled by the two sliding cam blocks 110 arranged within the presser base and supported on the bottom wall 52 thereof. Said blocks 110 are adapted to be reciprocated toward and away from each other and each cam block 110 is provided with two cam slots 111 arranged at substantially forty-five degrees to the path of movement of said blocks. Pins 112 are secured to said reciprocating members 97 and extend upwardly through slots 113 in the base of bottom wall 52 of said presser head and are provided at their upper extremities with cam rolls 114 which are arranged in said cam slots 111. It is seen by this arrangement the movement of said cam blocks 110 inwardly toward each other operates to cause said reciprocating members 97 to move diagonally inward to consequently withdraw the forming plates 105 from their extended position and a movement of said blocks 110 in the opposite direction serves to extend said forming plates.

Said cam blocks 110 are operated through the cam block 115 which is slidably arranged thereabove and is secured to a forming plate operating rod 116 slidably arranged in bearings in the two opposing walls 53 of the presser base and in an extended bearing 118 supported by the supporting arms 119 secured to said presser arm. Said cam block 115 is formed with two cam slots 120 therein which are ar-

ranged at substantially forty-five degrees to the path of movement of said cam. Pins 121 are secured in said cam blocks 110 and are upwardly extended and are provided with rollers 122 which are disposed within said cam slots 120.

It may be seen that a movement of said cam block 115 will cause said cam blocks 110 to be moved inwardly toward each other 10 to correspondingly retract said forming plates and a movement of said block 115 in the reverse sense will cause the extension of said plates.

The movement of said forming plate operating rod to cause the retraction of the forming plates from extended position, is controlled by the lower cam rod 125 which is slidably arranged in a rib 126 of the presser arm. Said rod 125 is connected 20 through a connecting member 125' to an extension rod 127 which is slidably arranged in a rib 76 of the presser arm beneath the extension rod 75 through which the movements of the presser frame are controlled. 25 Said extension rod 127 is extended beneath the cam block 80 into the space formed by the spacer block 86 between said cam blocks 80 and 85 and its end is provided with a downwardly extended pin which has a roller thereon arranged in the cam slot 130 in said cam block 85, which cam block serves to control the retraction of the forming plates.

The end of said lower cam rod 125 adjacent the rod 116 is provided with a contact block 131 which is caused to engage the end of said rod 116 to cause its movement in the retracting direction of the forming plates. It is desirable that the forming 40 blocks be locked in their fold defining position and for this purpose a slot 132 is formed in the upper side of said rod 116. A key 133 is slidably arranged in ways 133' in said wall 118 and surrounds said rod 116 45 and due to its weight, normally tends to fall and enter said slot 132 in said rod to thereby lock said rod from movement in either direction.

It is necessary that said key be removed 50 from locking engagement with said rod 116 before the contact block 131 of the lower cam rod 125 is moved into contact with end of said rod to actuate the same and for this purpose said rod 125 is provided with a projecting member 135 which is secured thereto 55 and which extends beneath said rod 116. Said key 133 at its lower end is formed with a cam surface 140 which, in a depressed or material clamping position of the presser head, is arranged in the path of movement 60 of the projecting member 135. Upon movement of the lower cam rod 125 previous to its engagement with rod 116 said extended member 135 is moved into contact with the 65 cam portion 140 of said key and serves to

raise said key from locking engagement with the slot 132 in said rod 116 and said key may be maintained in said locking position by means of the flat portion 135^a of said extension. A further movement of 70 said cam rod 125 causes the engagement of the contact block 131 with the end of said rod 116 to move said rod and thereby cause the retraction of the forming plates.

The presser head is provided with a 75 clamping plate 145 which is adapted to be brought into engagement with the material disposed on the material table 60 beneath said clamping plate to securely hold said material thereon during the folding operations of the machine and the weight of the presser head and its associated mechanism is adapted to be sufficient to securely hold the material against said table during the folding process without the provision of 80 additional weight or other clamping means.

The clamping plate comprises essentially a thin flat plate over which the forming plates are adapted to slide and which has dimensions approximately coinciding with 90 the inside dimensions defined by the folded edges of the material although it is obvious that the dimensions of said clamping plate can be varied considerably and yet securely hold the material in place during the various folding operations. The forming plates are adapted to be extended beyond the edges of said clamping plate to define the fold and to be retracted in from the edges of said clamping plate after the folding operation 95 has been completed.

The clamping plate is adjustably secured by means of screws 146 to feet 147 which extend upwardly and terminate in dovetailed portions 148 which are slidably arranged in correspondingly dovetailed portions 149 in the base 52 of the presser head. It is desirable to provide a different clamping plate with every substantial change in the dimensions of the folded material and 105 the adjustable arrangement of the clamping plate support permits this result to be accomplished.

It will be noted that, inasmuch as the feet are slidably arranged in the base of 115 the presser head, the feet may be moved inwardly toward each other to accommodate a clamping plate of smaller dimensions, or moved outwardly from each other to accommodate a clamping plate of larger dimensions. 120

The feet to which the clamping plate is supported are provided with the portions 150 and, with clamping plates of small dimensions, may be relatively reversed in the 125 ways in the presser base so that the toe portions point inwardly toward each other thereby the more effectively to provide for supporting the smaller sizes of the clamping plate.

After the presser head has been lowered to clamp the material to the material table, and the folding operation has been completed and the forming plates are retracted from the folded edge, it is necessary that the forming plates be again extended to condition the machine for a new folding operation. This extending operation of the forming plates is performed by the upper 10 cam rod 71 during the latter part of its movement to raise the presser head. For this purpose a forked lever is provided which is pivoted at 156 to a cross bracket 157 bolted to two adjacent cross ribs of 15 the presser arm and its two arms 155^a and 155^b are extended downwardly on each side of the upper cam rod 71 and the forming plate operating rod 116. A pin 158 is secured in the upper cam rod 71 to engage 20 said forked lever on one side and a pin 159 is secured in said operating plate rod 116 to engage said fork lever on the other side thereof.

In the operation of the machine, the 25 presser head is first moved downward to clamp the material to the material table and by the arrangement of the pin and upper cam rod, said rod is moved away from the forked lever 155 without actuating said lever which, however, falls by gravity 30 away from pin 159 and permits the rod 116 to move forward. The forming plates are thereafter retracted and the forming plate operating rod 116 is consequently 35 moved inward to accomplish this purpose and during the operation of the other component parts of the machine remains in this position.

After all operations upon the material 40 have been completed the presser head is raised and the upper cam rod 71 is for this purpose moved toward the right, see Fig. 4. In such movement the pin 158 carried thereby engages the arms of said forked lever 45 155 and moves it away from said presser head into engagement with the pin 159 carried by the forming plate operating rod 116 and consequently moves said rod outwardly to extend the forming plates which are thereafter locked in extended position.

In the operation of the machine, the material is first clamped to the material table with the forming plates extended to define the line of fold, the edges are folded over 55 the forming plates, the forming plates are withdrawn, the presser head is moved upward slightly and the creasing iron is brought into contact with the folded edge to firmly press the folded edge together and 60 form the ornamental marking thereon and is permitted to remain in such position for a suitable length of time by the clutching means above described, or by suitable dwell portions in the cams controlling the operation 65 of the component parts of the machine,

the presser head drops, the wipers and creasing iron are withdrawn, the presser head is moved completely upward and the forming plates are again extended for a new cycle of operation.

The cam path 16 of the cam disk 15, by which the component parts of the machine are operated, is provided with a dwell portion 16^a in which the cam roll 38 of the sliding cross head is adapted to be disposed at the end of a complete cycle of operation of the machine and when the clutch has operated to release the motor driven shaft from the clutch disk. The dwell portion 16^a is adapted to be of sufficient length 70 to permit a small rotary movement of said disk without affecting the component parts of the machine. The cam path 16 is also formed with an active portion 16^b which, with rotation of the cam disk, serves to move 75 the sliding cross head 35 toward the left, Fig. 1. The movement of said cross head causes the presser head to be moved downward and the cam groove 79, in the cam block 80 controlling the movements of said 80 presser head is formed with an active portion 79^a to cause such movement of the presser head. The downward movement of the presser head causes the material to be securely clamped to the material table and the 85 corners of the material to be turned up at the edge of the forming plates which are extended and locked in extended position to define the line of fold. The cam groove 79 is further formed with a dwell portion 79^b 90 therein which, with continued movement of the machine, serves to maintain the presser head in depressed position to permit the 95 operation of other component parts of the machine.

With continued operation of the machine, the side wipers 165 are moved inward by means described in the above named application and the corner wipers 166 are thereafter moved inward and the edge of the material is thereby folded over the forming plates. During this part of the operation of the mechanism, the forming plates are arranged to remain in extended position and the cam groove 130 in the cam block 85 100 controlling the movement of said forming plates is formed with a dwell portion 130^a to permit the movement of the cross head 35 without affecting the forming plates. Said dwell portion 130^a merges into an active 105 portion 130^b which has now been moved into engagement with the roller connected with the rod 127 which controls the movement of the forming plates and with continued movement of the cross head serves to retract said 110 forming plates.

The first operation in the retraction of said forming plates is the engagement of the end of the arm or extension 135 with the cam 140 of the locking key 133 to raise 115 120 125 130

said locking key from the slot 132 in the forming plate operating rod 116 to thereby unlock said rod. With continued movement of said extension 127 and the lower 5 cam rod 125, the contact block 131 is moved into contact with the end of said forming plate operating rod 116 and serves to move said rod forward to thereby retract the forming plates. During such movement the 10 locking key 133 may be maintained in elevated position by engagement with the flat or dwell portion 135^a of extension 135 or by the operating rod 116.

The edges have now been folded and the 15 forming plates withdrawn and the next step is the partial upward movement of the presser head which is performed by means of the portion 79 of the cam groove 79 at the end of the dwell portion 79^b thereof.

20 The creasing iron 170 is now moved into contact with the underside of the folded material and the folded edge is pressed against the wipers which are yet in their extended position, and the mechanism may be 25 arranged to remain in such position for a suitable period of time by the provision of a second dwell portion in said main cam groove 16 of the cam disk 15 at the end of the active portion 16^b therein; or by the 30 clutching means above described. With continued movement of said cam disk 15 the creasing iron 170 is moved downward away from contact with the material and the cam grooves 79 and 130 controlling the presser head and the forming plates are provided 35 with terminal dwell portions 79^b and 130^c respectively to permit the withdrawal of the creasing iron without causing a movement of said mechanism.

40 The sliding cross head 35 is now at the end of the stroke and returns under action of the cam driving disk 15. In its return, the sequence of operations is carried out in the reverse order and the presser head drops 45 and the lower cam rod 125 controlling the retraction of the forming plate is moved backward, but without effect on said forming plates, and near the end of the cycle of operation, the presser head is moved upwardly.

50 During its upward movement and through the forked lever 155 it serves to extend the forming plates to their original position where they are locked in such extended position. The cam disk 15 has now made one 55 revolution and the clutch is automatically disengaged and the machine is brought to rest with the cam roller 38 of the sliding cross head 35 in the dwell portion 16^a of said cam groove 16 and the machine is in condition 60 for the removal of the folded and creased material and the insertion of a new blank for folding.

I claim:

1. A material folding machine including a 65 base having a material receiving portion

within its border, a presser arm supported by said base and extended over said receiving portion and means pivotally connecting said arm and said base.

2. A material folding machine including a 70 base having a material receiving portion within its border, a presser arm supported by said base and extended over said receiving portion, means pivotally connecting said arm and said base, and means to lock said 75 presser arm to said base.

3. A material folding machine including a 80 base, a presser arm carried thereabove, a presser head mounted thereon reciprocable toward and away from said base, forming 85 plate operating means reciprocably mounted in said head, and a forming plate adjustably mounted on said operating means.

4. In a material folding machine, a presser 90 head, a member reciprocatingly supported by said head, a forming plate adjustable with respect to said member for the defining of differing dimensions of fold, and means securing said forming plate in an adjusted position to said member. 90

5. In a material folding machine, a presser head, a member reciprocatingly supported by said head, an adapting plate adjustably arranged thereon, and a forming plate adjustably carried by said adapting plate. 95

6. In a material folding machine, a presser head, a member reciprocatingly supported by said head, an adapting plate adjustably arranged thereon, a forming plate adjustably carried by said adapting plate, and 100 means securing said plates and member in adjusted position.

7. In a material folding machine, a forming plate of thin material, a forming plate support, means detachably securing said 105 plate to said support, an operating member, said support having means for adjustable connection with said operating member, and means to lock said support and operating member in any adjusted connection therewith. 110

8. In a material folding machine, a clamping plate of relatively thin material having feet rising therefrom for connection with a component part of the machine. 115

9. In a material folding machine, a presser head, a clamping plate of relatively thin material, a plurality of plate supporting feet, means detachably connecting said feet and plate, said presser head and feet having 120 coöoperating means which admit of the adjustable connection of said feet with said head.

10. In a material folding machine, a presser head, a material clamping plate, a 125 plurality of clamping plate supporting feet, means detachably securing said plate to said feet, said presser head having grooves therein, and said feet slidably arranged in said grooves. 130

11. In a material folding machine, a presser arm, a presser head reciprocatingly carried by said arm, a cam to reciprocate said presser head, and a cam to govern the movements of said first cam. 60
12. In a material folding machine, a presser arm, a presser head reciprocatingly carried by said arm and a cam carried by said arm to reciprocate said presser head. 65
10. 13. In a material folding machine, a presser arm, a presser head reciprocatingly carried by said arm, a cam to reciprocate said presser head, a cam governing the movements of said first cam, and means extended between said cams for the operation of said presser head. 70
14. In a material folding machine, a presser arm, a presser head reciprocatingly carried by said arm, a cam to reciprocate said head, forming plates carried by said head, a cam to extend and retract said plates, and a governing cam for said first cam. 75
15. In a material folding machine, forming plates extendible to define a line of fold and retractible from extended position, means to lock said plates in extended position, means to retract said plates, and means carried by said retracting means to unlock said forming plates. 80
16. In a material folding machine, forming plates extendible to define a line of fold and retractible from extended position, means to lock said plates in extended position, and means to retract said plates, said latter means serving to unlock said plates previous to the retracting operation. 85
17. In a material folding machine, a material table, a material clamping plate movable toward or away from said table, forming plates extendible to define a line of fold and retractible therefrom, and means to simultaneously operate said forming and clamping plates. 90
45. 18. In a material folding machine, a material table, a clamping plate movable toward and from said table, forming plates extendible to define a line of fold and retractible therefrom, means to actuate said clamping plate, means to actuate said forming plates, and means connecting both the aforesaid means to cause their conjoint operation. 95
19. In a material folding machine, a material table, a clamping plate movable to- 55
- ward and from said table forming plates extendible to define a line of fold and retractible therefrom, an operating rod for said clamping plate, an operating rod for said forming plates, and a lever connecting said two rods whereby a movement of one of said rods causes a movement of the other of said rods. 60
20. In a material folding machine, a material table, a clamping plate movable toward and away from said table, forming plates extendible to define a line of fold, and retractible therefrom, an operating rod for said clamping plate, means to operate it, an operating rod for said forming plates, and a pivoted lever connecting said rods whereby a movement of said clamping plate operating rod in one direction causes a movement of said other rod in the opposite direction. 65
21. In a material folding machine, a material table, a clamping plate movable toward and away from said table, forming plates extendible to define a line of fold and retractible therefrom, an operating rod for said clamping plate, an operating rod for said forming plates, a pivoted lever extended adjacent said rods, and means connecting said lever with said rods whereby a movement of one rod in one direction causes a movement of the other of said rods, and a movement of said rod in the other direction is without effect in moving said other rod. 70
22. In a material folding machine, forming plates to define a line of fold, and wipers to fold the material, and means to adjust said forming plates and wipers relatively to each other to admit of the folding of material of differing thicknesses. 75
23. In a material folding machine, forming plates to define a line of fold, and wipers to fold the material, said forming plates being movable to a position below the wipers, and means to adjust the position of said plates below said wipers to permit the folding of material to differing dimensions. 80
- In testimony whereof, I have signed my name to this specification, in the presence of two subscribing witnesses.
- JOSEPH W. ANTHONY.
